MUFFLER AND TAIL PIPE TOOL.

Filed April 19, 1949

FIG. 1.

FIG. 5.

FIG. 4.

FIG. 6.

A technical line drawing of a mechanical assembly, possibly a clutch or brake mechanism. The drawing shows a large, irregularly shaped base component on the left. A cylindrical part, labeled 10a, is attached to the top of the base. A horizontal rod or lever, labeled 13a, extends from the right side of the base. A curved component, labeled 16a, is attached to the base and connects to the lever. A small circular opening is visible on the base. A label '25' is placed near the center of the base. A label '12a' is placed near the bottom right of the base. The drawing is labeled 'FIG. 7.' at the bottom center.

FIG. 10.

MUFFLER AND TAIL PIPE TOOL

Clifford F. Ernst, Sandusky, Ohio

Application April 19, 1949, Serial No. 88,363

1 Claim. (Cl. 30—91)

1

This invention relates to tools for cutting and loosening automobile mufflers from their tail pipes, and an object is to produce a simple and efficient tool of this character which cuts or slits one of the telescoping tubes without injury to the other. Thus in one form, the tail pipe may be slit in that region telescoping within the muffler pipe but without injury to the muffler pipe, thus enabling the tail pipe to be removed without difficulty and enabling a new tail pipe to be mounted in position of use.

In another embodiment of the invention, the tool lends itself to slitting the muffler tube without injury to the telescoped tail pipe so that the tail pipe may subsequently be used again.

Embodiments of the invention are shown by way of illustration in the accompanying drawings, in which

Figure 1 is a perspective view of an automobile muffler and telescoped tail pipe and showing the tool in position of use for slitting the muffler tube without injury to the tail pipe;

Figure 2 is a front perspective view of the working or slitting end portion of the tool;

Figure 3 is a top plan view of the slitting end portion of the tool shown in Figure 2;

Figure 4 is a transverse sectional view on the line 4—4 of Figure 3;

Figure 5 is a front end elevation of the tool;

Figure 6 is a fragmentary view of an automobile muffler and tail pipe assembly, showing a portion of the tail pipe slotted to receive an alternate form of tool by which the tail pipe is slit without injury to the muffler tube or flange;

Figure 7 is a view similar to Figure 6, but showing an alternate form of tool in position of use for slitting the tail pipe without damaging the muffler flange or tube;

Figure 8 is a top plan view of the slitting end portion of the tool shown in Figure 6, showing particularly the transverse curvature to fit the inside of the muffler flange;

Figure 9 is a front perspective view of a fragment of the slitting end portion of the tool shown on Figures 7 and 8; and

Figure 10 is a transverse sectional view on the line 10—10 of Figure 8.

The illustrated embodiment of the invention comprises an automobile muffler 10 having an integral flange pipe 11 with which the tail pipe 12 telescopes in the usual manner. As is well recognized in this art, these telescoped pipes become so bound together due to rust, road grime, etc., that oftentimes an extremely difficult problem is presented of separating these pipes.

2

Not infrequently, they become so mutilated during the operation that they are rendered worthless. According to the form of the invention illustrated on Figures 1 to 5, a simple shearing or slitting tool is provided by which the muffler flange pipe 11 is slit without damage to the tail pipe so that although the muffler may have to be discarded, the tail pipe can be reused. As shown, the tool consists of a handle or shank portion 13, 5 and a slitting end portion 14 integrally united to each other. The handle and slitting portions are arranged in parallel relationship but offset laterally from each other by a bend 15. The slitting end portion 14 consists of an elongate plate 16, the under side of which is curvilinear transversely throughout its length, the contour being such as to fit the outside of the tail pipe 12 and to slide along such surface.

Integral with the plate 16 midway of the upper 20 side projects a rib 17 which is of uniform thickness at its upper edge portion throughout its length. The front end of the rib 17, in this instance, is inwardly curved as indicated at 18 to provide a cutting or shearing edge which engages the metal of the muffler tube flange 11 and progressively slits it. At one side of the shearing edge 18 and slightly rearwardly thereof extends a surface 19 which gently curves rearwardly. The curved surface 19 merges with a flat surface 20 which extends substantially throughout the length of the slitting end portion and is disposed at right angles to the side 21 of the rib 17. At the opposite side of the rib is a surface 22 which extends rearwardly from the shearing edge 18 25 to form a plow-like cam surface which operates progressively to curl the portion slit from the flange tube 11. The surface 22 merges into an inclined surface 23 which serves laterally to cam the slit portion as the slitting operation advances. 30 It should be noted that the surface 24 of the rib directly in rear of the shearing edge 18 and above the plow-like cam 22 is flat and cooperates in piloting the tool as it progressively shears the metal from the tube flange 11. 35

40 From the above description, it will be apparent that the under side of the tool rides along the tail pipe 12 without injuring it, the shearing or slitting operation taking place above the tail pipe so that once the tube flange 11 is sheared or slit sufficiently, the tail pipe 12 may be readily removed.

In the form of the invention illustrated on Figures 6 to 10, the tail pipe 12a is slit without injury to the muffler tube flange 11a. In this case, the tail pipe 12a is first formed with a slot

25 by means of a chisel or other suitable instrument. The length of the slot 25 should be sufficient to enable the slitting end portion 14a of the tool to be inserted. This tool is similar to that above described, except reversed or the plate 16a has its upper side curved transversely throughout its length, the curvature being such as to fit the inside of the tube flange 11a so that the surface 16a rides along the inner surface of the tube flange 11a throughout the operation of slitting the tail pipe 12a. Thus the riding surface 16a is convex whereas the riding surface on the plate 16 in the tool illustrated in Figures 1 to 5 is concave in cross section. The working or slitting side of the tool illustrated on Figures 6 to 10 is similar to that above described so that detail description is not considered necessary. In this tool, it will be manifest that the slot 25 must first be formed in the tail pipe 12a adjacent the tube flange 11a and this slot must be of sufficient length to enable the slitting end portion of the tool to be inserted before the slitting of the tail pipe directly beneath the tube flange 11a is started. Thereafter, the slitting can be easily accomplished, it being merely necessary, as in the tool above described, to use a hammer against the opposite end of the tool and progressively slit the tube until the tail pipe can be freed from the muffler tube flange.

In the form of the invention illustrated in Figures 6 to 10, the same reference numerals are used but with the exponent a to designate like parts.

It is to be understood that numerous changes in details of construction, arrangement and operation may be effected without departing from the spirit of the invention especially as defined in the appended claim.

The words "tail pipe" used in the specification and claim shall also include the exhaust pipe which is connected to the front end of the muffler.

What I claim is:

A tool for slitting one of a pair of telescoped

cylindrical pipes while utilizing the other one of the pair as a guide pipe, said tool comprising a handle portion and a slitting end portion, said handle portion being parallel to but offset laterally from the slitting end portion, the slitting end portion including an elongate plate member having one face transversely curved throughout its length such as to be adapted to fit and slide over the curved surface of the guide pipe, a rib projecting at substantially right angles from the other face of the plate member extending longitudinally and substantially centrally thereof and with the outer edge portion of uniform thickness throughout, said plate member having a cutting edge at the front thereof, a substantially up and down cutting edge at the front of said rib, one side of said rib being flat and straight whereby to engage against one edge of the slit being cut, the plate surface adjacent the flat side of the rib being flat and straight and being at right angles thereto whereby to serve as a guide member for engaging beneath the pipe being slit, a plow-like cam surface on the plate member lying on the opposite side of said rib, said cam surface being arranged rearwardly of said cutting edge, the surface continuing rearwardly from the rear and highest point of said cam surface being transversely concave and merging with the rib and plate to cooperate in piloting the tool during the slitting operation.
